UNITED STATES PATENT OFFICE

REGINALD G. STANDERWICK, OF MARBLEHEAD, MASSACHUSETTS, ASSIGNOR TO
GENERAL ELECTRIC COMPANY, A CORPORATION OF NEW YORK

ELASTIC FLUID TURBINE

Application filed November 26, 1932. Serial No. 644,461.

The present invention relates to elastic fluid turbines wherein elastic fluid is extracted from or admitted to the turbine at two intermediate points of different pressures, and has for its object to provide an improved governing mechanism for a turbine of this type.

For a consideration of what I believe to be novel and my invention, attention is directed to the following specification and the claims appended thereto.

In the drawing, the figure is a diagrammatic view, partly in section, of an elastic fluid turbine provided with a governing mechanism embodying the invention.

Referring to the drawing, 1 indicates an elastic fluid turbine having an admission conduit 2 and an exhaust conduit 3 which may exhaust to a suitable condenser (not shown).

20 In conduit 2 is a valve means 4 for regulating the flow of elastic fluid to the turbine.

Connected to turbine 1 at two intermediate points of different pressures are two conduits 5 and 6 through which elastic fluid may be extracted from the turbine or admitted to the turbine. Conduit 5 is connected to the turbine at a point of higher pressure than is conduit 6. The flow of elastic fluid from the turbine stage to which conduit 5 is connected to the next lower stage is controlled by the valve means 7, and the flow of elastic fluid from the turbine stage to which conduit 6 is connected to the next lower turbine stage, is controlled by the valve means 8. The speed governor for the turbine is indicated at 9, being shown as driven from turbine shaft 10 through beveled gears 11.

The turbine construction so far described is shown diagrammatically, the several valves 4, 7 and 8 being shown in a simplified manner. It will be understood that valve means 4 represents any suitable high pressure valve mechanism and that valve means 7 and 8 represent any suitable type of intermediate valve means. Ordinarily, the intermediate valve

means is of the ring valve type such as that shown in the patent to Norton, 1,091,078.

The elastic fluid turbine may drive any suitable load such as, for example, an alternating current electric generator. The generator may or may not be tied into a system comprising other alternating current generators.

My invention relates particularly to means for adjusting valve means 4, 7 and 8 whereby the elastic fluid turbine may be regulated for changes in load and also to maintain substantially constant pressure in the two stages to which conduits 5 and 6 are connected.

Speed governor 9 has a spindle 12 connected to a lever 13 having at one end a fixed fulcrum 14. The other end of lever 13 is connected by a link 15 to one end of a floating lever 16. The other end of floating lever 16 is connected to the stem 17 of a pressure responsive device 18. Pressure responsive device 18 may be in the form of a corrugated bellows, a piston and cylinder, or the like. In the present instance, I have shown it more or less diagrammatically as comprising a casting provided with a flexible diaphragm 19 to which the lower end of stem 17 is connected. Associated with the diaphragm is a suitable adjusting spring 20. Pressure responsive device 18 is connected by a pipe 21 to conduit 5 so that the pressure responsive device is actuated in accordance with the pressure in the higher pressure turbine stage to which conduit 5 is connected.

Valve means 4 is connected by a stem 22 to one end of a lever 23 pivoted intermediate between its ends on link 15 as is indicated at 24. The other end of lever 23 is connected by a link 25 to one arm 26 of a three arm lever, the other two arms being indicated at 27 and 28. The three arm lever is pivotally supported on lever 16 as is indicated at 29. Arm 26 is connected by a stem 30 to valve means 8 and arm 27 is connected by a stem 31 to valve means 7. Arm 28 is connected by a link 32 to

one arm of bell crank lever 33, the other arm of which is connected to the stem 34 of a pressure actuated device 35 similar to pressure actuated device 19. Pressure actuated device 35 is connected by a pipe 36 to conduit 6 whereby such pressure actuated device is responsive to the pressure in the lower pressure stage of the turbine to which conduit 6 is connected.

10 The operation is as follows:

Assume that the turbine is operating, carrying a certain load, that elastic fluid is being extracted from or supplied through conduits 5 and 6, and that under the operating 15 conditions obtaining, with valve means 4, 7 and 8 in the positions shown, sufficient elastic fluid is admitted to the turbine through valve means 4 to carry the load on the turbine and maintain a flow past valve means 7 and 20 8 such that the desired pressure obtains in the stages of the elastic fluid turbine to which conduits 5 and 6 are connected.

If the load increases, the turbine speed will decrease whereupon speed governor 9 will 25 move the right hand end of lever 13 upward, the lever turning on its pivot 14. The upward movement of the right hand end of lever 13 lifts link 15 which in turn raises the left hand end of lever 23 and the left hand 30 end of lever 16, lever 23 pivoting on link 25 and lever 16 pivoting on stem 17. Upward movement of the left hand end of lever 23 opens further valve means 4 and upward movement of the left hand end of lever 16 35 lifts bodily the three arm lever comprising arms 26, 27 and 28 and thus opens further, valve means 7 and 8. When the three arm lever moves upward, link 32 pivots on the one arm of bell crank lever 33. It will thus be 40 seen that upon an increase in load (i. e., a decrease in turbine speed) speed governor 9 operates to open each of the valve means 4, 7 and 8. The opening of valve means 4 admits more elastic fluid to the turbine and the 45 opening of valve means 7 and 8 permits more elastic fluid to flow from the stages to which conduits 5 and 6 are connected to the next lower stages, thus maintaining the pressures in such stages substantially constant. In this 50 connection, it will be understood that the several lever arms and the valve means are so correlated relatively to each other that the respective movements of the valve means will be such as to effect the desired result. In case 55 of an increase in turbine speed which may be due to a decrease in load, the speed governor 9 moves lever 13 in an opposite direction, thus simultaneously moving the valve means 4, 7 and 8 toward closed positions.

60 Assume now that the pressure in the higher pressure turbine stage to which conduit 5 is connected increases which may be due for example to a decrease in flow of elastic fluid through conduit 5 away from the turbine or 65 an increase in flow of elastic fluid through

conduit 5 toward the turbine. When increased pressure in conduit 5 actuates the pressure responsive device 19, moving upward the right hand end of lever 16, the upward movement of the right hand end of lever 16 lifts the three arm levers 26, 27 and 28 vertically, thus opening further the valve means 7 and 8. At the same time, this upward movement turns lever 23 on its pivot 24 moving valve means 4 toward closed position. The opening of valve means 7 and 8 functions to permit more elastic fluid to flow through the turbine, the opening of valve means 7 being sufficient to effect the desired decrease in pressure in the stage to which conduit 5 is connected, and the opening of valve means 8 being sufficient to prevent an increase in the pressure in the stage to which conduit 6 is connected due to the increased flow to it caused by the opening movement of valve means 7. At the same time, the movement of valve means 4 toward closed position serves to decrease the amount of elastic fluid admitted to the turbine, this offsetting the additional elastic fluid now flowing through the lower pressure stages of the turbine and thus preventing an increase in speed of the turbine. If the pressure in the stage to which conduit 5 is connected decreases, an action similar to that just described takes place except in the opposite sense, valve means 7 and 8 being both moved toward closed positions and valve means 4 being moved toward open position.

In case the pressure in the stage to which conduit 6 is connected increases, pressure responsive device 35 is actuated to turn bell crank lever 33 in a counter-clockwise direction. This turns the three arm lever comprising arms 26, 27 and 28 in a counter-clockwise 105 direction, the lever pivoting on its fulcrum 29, moving valve means 7 toward closed position and valve means 8 toward open position. At the same time, through link 25 and lever 23, valve means 4 is moved toward closed 110 position. Movement of valve means 8 toward open position serves to permit more elastic fluid to flow from the stage to which conduit 6 is connected to the low pressure portion of the turbine, thereby reducing the pressure in this stage of the turbine. At the same time, the movement of high pressure valve means 4 toward closed position serves to decrease the amount of elastic fluid being admitted to the turbine so as to compensate 120 for the additional elastic fluid now flowing past valve means 8, thus serving to prevent increase in speed of the turbine, and movement of valve means 7 toward closed position serves to maintain constant the elastic fluid 125 pressure in the turbine stage to which conduit 5 is connected. If the pressure in the turbine stage to which conduit 6 is connected decreases, the mechanism operates in a similar manner except in the opposite directions, 130

valve means 8 being moved toward closed position and valve means 4 and valve means 7 being moved toward open positions.

With the foregoing arrangement, it will be seen that I provide a governing mechanism for an elastic fluid turbine having conduits connected to two stages of different pressures through which elastic fluid may be admitted to or extracted from the turbine which will 5 function to regulate the turbine both in terms of load (i. e., speed) and in terms of stage pressures whereby the speed and the pressures in the two stages to which conduits 5 and 6 are connected will remain substantially 10 constant. In the present instance, I have shown the speed governor 9 and the pressure responsive devices 19 and 35 connected directly to the valve means. It will be understood, however, that ordinarily they will be 15 connected to the valve means through the intermediary of servo-motors. The servo-motors have not been illustrated as their omission simplifies the drawing, making the principle of my invention more readily comprehended.

In constructing the regulating mechanism, the several levers and connections are so proportioned that the rate of travel of the high pressure valve means 4 and the valve means 30 7 and 8 relatively to each other is such that when a variation in load occurs with constant pressures in the stages to which conduits 5 and 6 are connected, the several valve means are so operated that the quantity of 35 elastic fluid going all the way through the turbine from the high pressure end to the exhaust end will be passed through the valve means 7 and 8 without disturbing the pressures existing in the stages to which conduits 40 5 and 6 are connected. This result is accomplished by properly proportioning the travel of the pressure responsive devices with respect to the valve areas of the several valve means 4, 7 and 8.

45 What I claim as new and desire to secure by Letters Patent of the United States is:

1. An elastic fluid turbine having valve means for controlling the admission of elastic fluid thereto, two conduits connected to 50 the turbine at stages of lower pressure therein, valve means for regulating the flow of elastic fluid from said stages to the next lower stages, a three arm lever having two of its arms connected to said regulating valve means, a floating lever on which the three arm lever is pivoted, means responsive to the pressure in one of said stages connected to the floating lever, means responsive to the pressure in the other of said stages connected 55 to the other arm of said three arm lever, a third lever connecting the three arm lever to said controlling valve means, a speed governor, and means connecting the speed governor to said third lever and to said floating 60 lever.

2. The combination with an elastic fluid turbine having conduits connected to it at a higher pressure stage and at a lower pressure stage for flow of elastic fluid to or from the turbine, valve means for controlling the flow of elastic fluid to the turbine, and a higher pressure stage valve means and a lower pressure stage valve means for regulating the flow of elastic fluid from said stages to the next lower stages, of a speed governor, a 70 pressure responsive device connected to the stage of higher pressure, a pressure responsive device connected to the stage of lower pressure, and lever mechanism connecting the speed governor to said three valve means for moving them simultaneously in the same direction, connecting the first named pressure responsive device to said valve means to move the first named valve means in one direction and the other two valve means in the other direction, and connecting the second named pressure responsive device to said valve means to move the first named valve means and the second named valve means in one direction and the third named valve 75 means in the other direction.

In witness whereof, I have hereunto set my hand.

REGINALD G. STANDERWICK.
